FOLDING MACHINE

William Jonathan Neidig, Chicago, Ill.

Application July 10, 1929, Serial No. 377,255

23 Claims. (Cl. 270—66)

The invention relates to mechanisms designed to fold sheets of cut paper or similar material, more especially sheets of varying size, such as commonly require the folding mechanism to be frequently adjusted, as in usual commercial job folding or office folding.

The invention comprises a number of features novel in the art. These include a novel mode of operation, of especial advantage in some uses because of the ease with which the position on the sheet of longitudinal folds may be varied, including the usual parallel folds employed in folding letters or the like. This aspect of the invention is illustrated not only by the embodiments described herein, but by the related embodiments described and specifically claimed in my United States Patent No. 1,838,106, dated December 29, 1931, and in my co-pending application, Serial Number 582,142, filed December 19, 1931, the latter containing a clear explanation of the relationship existing between these several embodiments, although the invention is not limited to these embodiments.

Other features of the invention are likewise further illustrated in these related embodiments, in some cases by specific variations that are specifically claimed in the said patent or said co-pending application. These include novel gated constructions useful in various paper folding, forwarding, pressing and discharging operations. They also include novel adjusting means, to facilitate changing the position of certain folds upon the sheet.

The invention includes a novel gated construction useful in entering sheets intended to be passed through the first-stage folding mechanism without being folded thereby.

The general objects of my invention are to supply an improved folding mechanism for job and office folding, embodying such of these features as may be found desirable for the use in mind, thereby enabling the operator to make quicker and more convenient adjustments, and to make these even while the machine is running, and without the possession of any great skill on his part.

I attain my several objects by the mechanism illustrated in the accompanying drawings, in which—

Figures 1 and 1^a constitute together an end view of one of the embodiments of my invention, Fig. 1^a being a continuation downwardly of Fig. 1, the sheet being shown advanced to a position in which it is about to be acted upon by my folding means along a line parallel to the

direction of its movement; Fig. 2 is a diagrammatic view looking downward, on the line A—A, showing the transverse position of the sheet at that time; Fig. 3 is a diagrammatic view of the same, still looking downward on the line A—A, after the sheet has been slightly advanced, showing the forming upward it has received from right-hand and left-hand forming members; Fig. 4 is a detail view of the same, showing the construction of certain of said members; Fig. 5 is a view looking downward on the line B—B, but with the sheet still further advanced; Fig. 6 is what would correspond to a plan view of portions of Fig. 1 if the down-standing mechanism were shown in horizontal position, the left-hand and right-hand members thereof corresponding to the left-hand and right-hand members of Fig. 5; Fig. 7 is a detail view, partly broken away, of a transverse folding roll shown in Fig. 1; Fig. 8 is a view looking downward on the line C—C, Fig. 1, showing certain details of construction; Fig. 9 is a view in section of the transverse folding rolls shown in Fig. 1; Figs. 10, 11 and 12 illustrate diagrammatically the action of a recessed transverse folding roll when the sheet is required to be entered without receiving the transverse fold; Fig. 13 is an end view of a modification of the mechanism shown in Fig. 1; Fig. 14 illustrates details of construction of the same.

In the embodiments of the invention shown in the drawings use is made of a usual folding knife 1, attached upon arms 2, which are in turn attached upon shaft 3 journaled in end frames 4. The knife may be operated in any approved manner; in the drawings it is operated by a gear wheel 7 having attached upon it a cam 8, through cam roller 9 on arm 2. The cam strikes it downwardly in such manner as to carry a sheet lying across its path into the bite of transverse folding rolls 5 and 6, spring-pressed together, which thereupon pull it between them. Said rolls are connected with toothed wheel 7 through toothed wheel 11 and means later described, and are rotated thereby an even number of times for each revolution of wheel 7. The knife may be returned into the position shown by usual means, such as spring action.

I depart from common practice in the construction of folding rolls 5 and 6 by supplying either one or both with a longitudinal recess 12. The purpose of the recess is to act as a kind of gateway permitting the knife to introduce difficult stock between the said rolls, such as thick stock or stock already folded or stock having a finish difficult for the rolls to grasp. The action is

shown clearly in Fig. 9. The recess construction can be used also to soften the fold to resemble the fold done by hand. It also facilitates the withdrawal of the knife, rendering its use with small rolls less exact in depth of stroke. It also facilitates the entering between the rolls of an unfolded sheet-edge. By using a recessed roll the sheet can be positioned forwardly as in Fig. 10 to a point permitting the leading edge when bent downward by the knife to reach the point of closure between the rolls. If a roll is used not supplied with a recess, either the downward-carried end of the sheet will meet with interference from the roll and receive a fold, or the sheet must be advanced after the end of the sheet is carried past the contour of the roll. In either case the sheet is not very certainly entered. It will be understood that some uses of my invention will not require such a recess, and in such cases it will not be employed.

It will be noted that I prefer to employ a roll or rolls constructed like that shown in Fig. 7, in which the recess or gateway 12 does not extend quite to the end of the roll, the purpose of such construction being to enable the solid or unrecessed ends of the roll to act as bearers, so that the revolving rolls will run smoothly together, instead of being spring-pressed into a trough at each revolution, but I do not limit myself to any precise means of controlling their approach to each other.

It will be noted also that the use of such a recess does not materially affect the action of said rolls in their function of sheet-advancing means, since the width of the recess is too slight to affect the progress of the sheet materially, and such effect as obtains is exerted evenly, and furthermore, before the roll completes a revolution to present the recess again to the sheet, the leading edge of the sheet will have passed upon sheet-advancing wheel 41, to be described later. The progress of the sheet may be regarded as continuous, in such a case, and is so in fact.

Folding rolls 5 and 6 just described are carried upon shafts 13 and 14 journaled in end frames 4. Attached upon said shafts are gears 15 and 16 meshing together, connected through gear 17 with gear 7, journaled upon pin 10, which is driven by gear 19 on shaft 20, journaled in end frames 4.

The mechanism described is that which I prefer to employ for making a transverse fold, that is to say, a fold at right angles to the direction of progress of the sheet. I will now describe the means shown in the drawings for making one or more parallel folds. By a parallel fold I mean a fold parallel with the direction of progress of the sheet, and not necessarily one parallel with another fold.

I prefer to use sheet-advancing means giving the sheet a substantially continuous progress, and folding means operative while the sheet is moving, although I do not in all cases limit myself thereto.

I prefer to use revolute means for making said one or more parallel folds, but the invention is not limited to revolute means.

In the embodiments of my invention shown in the drawings I employ means for making two parallel folds, said means being revolute, and operating while the sheet is in motion. One of said folds, that made by the mechanism arbitrarily shown in Fig. 5 and other figures as positioned at the left-hand side of the drawing, will be referred to hereafter as the left-hand fold, and

the mechanism making it as the left-hand folding unit. The other of said folds, made by the mechanism arbitrarily shown in said figures as positioned at the right-hand side of the drawing, will be referred to hereafter as the right-hand fold, and the mechanism making it as the right-hand folding unit. The two folds are made independently. Either may be begun first and either completed first. In the present embodiments they are begun simultaneously; but the right-hand fold is shown as completed first, and the left-hand as lapping thereover and completed last. It will be noted that either the left-hand or the right-hand fold may be made alone, using the mechanism shown in the drawings, at the will of the operator.

The left-hand folding unit, shown in end view in Fig. 1, will first be described.

The framework of said unit consists of two similar frame pieces 23, held at a suitable distance apart by shouldered stays 25. The right-hand folding unit employs a similar framework. Frames 23 are suspended slidably at two points upon transversely extending guides or rods 24, attached at either end upon end-frames 4, in the case of both units. An upwardly extending frame extension 52 is supported on frames 23 by means of shouldered stays 53 in both cases, from the nearer side or end-frame side in the case of the left-hand unit, and from the further or end-frame side in the case of the other.

Journaled in said frames 23, both of the left-hand folding unit and of the right-hand (see Figs. 1 and 1^a), are the short shafts 26, 27, 28, 29, 30, 31 and 32, and a longer common drive shaft 20, previously described as journaled also in end-frames 4. Said shaft 20 contains a keyway 35 running longitudinally thereof, adapted to receive a sliding key 34 attached upon a sliding miter gear 36 in the case of both units. Miter gear 36 meshes drivingly with miter gear 33, attached upon shaft 37, which is journaled at 38 upon frame 23. Miter gears 39 attached upon said shaft in turn mesh drivingly with miter gears 40 attached upon shafts 26, 27, 28, 29, 30, 31 and 32. 45 Similar driving means between said shafts and drive shaft 20 are employed in the mechanism of the right-hand unit. It will be understood that the several toothed wheels shown in the drawings are of related dimensions so as to give the parts 50 driven thereby a timed operative relationship. Thus in the drawings rolls 5 and 6 are geared to rotate six even times for each revolution of toothed wheel 7, and therefore for each stroke of knife 1, and shaft 20 and its supported wheel 41, and the gear-driven revolving parts on separable frames 23, including wheels 42, 44, 46, 48, 49, 50, 60, 62, 64, 65, 66 and 67, are geared to rotate three even times for each revolution of toothed wheel 7. The construction described has 60 for its purpose the maintaining of a timed relationship between the operative members of said units, and between said units and the mechanism previously described. It is chosen for its convenience. Other connecting devices for the purpose are shown in Fig. 13. The invention is not limited to any of these.

The revolute members more directly concerned with the folding operation, as shown in the present embodiment illustrated in Fig. 1, in most 70 cases have a plurality of functions, divided between sheet-advancing, forming, guiding and controlling the sheet, and laying down the completed fold.

The first of these to be described is wheel 41, 75

which is keyed slidably upon shaft 20 and slides with frames 23 thereon, maintaining meanwhile its lateral position with respect to said frames. Its function is to advance and control the sheet, 5 or assist in doing so, cooperating with spring wheel 58, to be described later, and other sheet controlling members. The right-hand unit is supplied with a similar wheel, similarly connected.

The second of these members to be described is wheel 42, attached upon shaft 26. It is supplied at the folding line with a folding or forming flange 43, said flange being partly cut away, the open portion acting as a kind of revolute gateway to permit the leading edge of the sheet to pass 10 upon the sheet-advancing portion of said wheel 42 without being acted upon formingly by said flange. In the embodiment illustrated the flange is cut away sufficiently to delay the forming action until the leading edge of the sheet comes under 15 the control of wheel 44, in order that both wheels may act formingly upon the sheet at the same time, the chance of displacement being thereby lessened. Wheel 44 is attached upon shaft 27. It too is supplied with a forming flange, indicated at 45, that is partly cut away in a gateway, to permit the leading edge of the sheet to pass upon the sheet-advancing portion of said wheel in advance of action by the flange. By employing such gated means the sheet is securely 20 held by both wheels during the forming action of the flanges. Wheels 42 and 44 and their driving connections are repeated in the right-hand folding unit, except that flanges 43 and 45 are in right-hand position with respect to said wheels, 25 rather than in left-hand.

Up to this point both the right-hand and left-hand units act simultaneously in forming up the sheet along the folding line; but inasmuch as the right-hand unit completes its fold in advance 30 of the left-hand, from this point the revolute members mounted opposite each other differ slightly in their timing, and therefore in their action.

I will continue to describe the left-hand unit. 40 Wheel 46 thereof, attached upon shaft 28, is supplied with a continuous flange 47 in line with the flanges previously described, that is to say, on the folding line. This flange does not act formingly 45 upon the sheet, which has already been formed up, but it acts guidingly thereon, in connection with other structure to be described. It has no counterpart in the right-hand unit, being in the nature of an idle wheel.

Wheels 48, 49 and 50 are attached respectively 50 upon shafts 29, 30 and 31, as are similar wheels operating in the right-hand folding unit, and a further similar wheel 46^b upon shaft 28 opposite wheel 46 (Fig. 6). These wheels extend beyond the folding line in each case, so as to serve as 55 bearers to support cooperating wheels 60, 61 and 62, on the left-hand unit and wheels 64, 65, 66 and 67 on the right-hand unit. Wheels 60, 61, 62, 66 and 67 are driven respectively from shafts 29, 30, 31, on the left-hand unit, and 29 and 60 65 on the right-hand, through miter gears 8, one member of which is attached to said shafts and the other to up-standing axles 33 with which 65 said wheels are supplied, said axles being journaled in an extension of frame 23. Wheels 64 and 65 on the right-hand unit do not require a timed drive, but are driven by friction by the wheels upon which they rest. The timed members among said wheels are supplied with gateways or cut away portions permitting the leading 70 edge of the sheet to pass upon their engaging

wheels without being acted upon foldingly, somewhat in the manner described in connection with wheels 42 and 44. Said members extend past the folding line in a position approximately horizontal to the sheet, except where they are gated or cut away, and are spring-pressed downwardly upon the wheels shown as cooperating therewith (Fig. 6) by means of springs 69 (Fig. 5), as are also the untimed wheels 64 and 65, which merely act sealingly upon an already completed fold and 10 assist in advancing the sheet.

Other cooperating structure will now be described. Frame extension 52, already referred to, has attached upon it an inwardly extending member 54, supported at the inner end by yoke-piece 55 sliding upon shaft 56, said shaft being attached at either end in end-frames 4. Member 54 serves to support piece 57 attached upon it, in which are journaled spring-pressed wheels 58, each supplied with an axle 59. The spring 20 pressure is conveniently supplied by making said wheels of a resilient material like thin spring steel.

The purpose of the said wheels is to hold the sheet against wheels 41, 42 and 44, so as to 25 cause it to partake of their movement, and to act as a support over which the sheet is formed up at the folding line. I prefer to employ a revolute support such as this behind the forming-up means, but stationary tongues or guide-straps 70, attached upon piece 57 by means of blocks 71, act to some extent as a support over which the sheet is formed up. Said straps are preferably made of smooth spring steel. They are shown in Figs. 4 and 6 as recessed over the 30 apex of the several wheels engaging the sheet so as to avoid interference therewith. It is to be noted that the edges of such recesses are slanted away sharply so as to act guidingly upon the leading edge of the formed-up sheet without 35 obstructing its progress.

Other forms of wheels having the functions of wheels 56 are shown in Fig. 13, and other forms of spring pressure engaging said wheels with the sheet. The invention is not limited to any particular form of either.

To assist in supporting the sheet in its plane of movement I attach a support or paper table 105 upon frames 23, said paper table being pierced to permit the various revolute members with which it would interfere to project through it. I also attach an intermediate paper support 106 upon rods 24, at a point midway between the folding units suspended thereon. Whatever the lateral position of said units, said paper support 55 will lie midway between them.

It will be understood that the structure just described, with the exception of midway paper support 106, is described also with respect to the right-hand folding unit.

The stacking means shown in the drawings is no part of my invention, which in practice will use any approved stacking means found most useful. As shown in the drawings.

Shaft 32, driven as described, has attached 65 upon it bevel gear 12 meshing with bevel gear 73 on upstanding shaft 14, journaled in frame extension 75. Shaft 14 is preferably positioned near the folding line. Carried upon it by means of an attached collar is helical member 76 that 70 extends past the folding line in contour, said member being shaped and timed to present an uninterrupted opening or gateway to the leading edge or end of the folded sheet. In the drawings, it is shown turned in gated position, ready 75

to act liftingly upon such a sheet. The sheet is brought to a stop by tray 17. Upon the further revolving of said helical member the sheet is lifted out of the paper path against the sheets previously folded, indicated at 18. A side guide 19, like tray 17 attached upon frame 23, cooperates in holding the folded sheets in convenient position. The tray and guide will have any desired capacity, and after they are filled the 10 folded sheets may pass out upon a table top or other receptacle. Guide 19 may be constructed to bear lightly against the sides of the folded stock. Said structure is repeated in the right-hand unit.

15 The right-hand and left-hand units described are slidable laterally upon supports 24 both with respect to end frames 4 and with respect to each other. Their separable relationship is provided in order that the operator may vary the relationship of his parallel folds. It will be noted that they may be separated to an extent permitting the passage of a sheet upon them without folding. In practice single folds made transversely are often required. It will be noted also that 20 they can be made to act foldingly along a single parallel folding line, instead of a double. Such use is also frequently required in commercial practice.

Said separable folding units are preferably held 30 in lateral position by means of the following devices:

Extending transversely between end frames 4 and journaled therein are threaded shafts 80 and 81. The threaded portions of said shafts 35 are preferably given a right-hand thread upon one side of center and a left-hand thread upon the other. Said threads correspond in pitch in the case of both shafts. Said threaded shafts engage suitably with threaded holes in frames 40 23, both on the right-hand and left-hand units, so that when rotated similarly either shaft will give the respective units the same lateral movement. I secure identical rotation for said shafts by attaching upon each a sprocket wheel 82 45 identical in size and connecting the two by means of chain 84. A hand wheel 85 attached upon shaft 81 furnishes a convenient handle for rotating the shafts.

As will be seen, said adjusting means will act 50 always to preserve the parallel relationship between the right-hand and left-hand folding members without care on the part of the operator. As will be seen also, the use of said adjusting means will not in any way affect the folding action of 55 the units. In commercial practice this will be found a great advantage.

The action of the mechanism will be described 60 when folding a common letter. The sheet to be folded, indicated later at 107, is laid in position across the transverse folding rolls 5 and 6, knife 1 carries the same between said rolls, the sheet is folded thereby, and it is then advanced to the 65 position shown in Figs. 1 and 2. A moment later flanges 43 and 45 act synchronously to form up the sheet as shown in Fig. 3. Upon being further advanced the sheet is acted upon by gated sealing wheel 67 (Fig. 6) of the right-hand folding unit, and the right-hand upstanding portion is laid down thereby. The left-hand upstanding 70 portion remains standing during said action. A further advance presents the leading end or edge of the sheet to gated wheels 60 and 69. Wheel 69 of the right-hand unit immediately proceeds to complete or seal the right-hand fold, but gated wheel 60 of the left-hand unit permits the up- 75 standing left-hand fold to remain as it is for the moment without being laid down or sealed. Said upstanding portion of the sheet is carried forward past gated wheel 61 without being acted upon and the leading end presented to the recess in gated wheel 62. The purpose of the delay is to permit the right-hand fold to be securely laid down after the trailing end of the sheet has passed the interference of wheels 58 and their supports. The sheet during this time is advanced by the right-hand sheet advancing members, and it is guided by tongues or guides 70. Upon arriving at gated wheel 62, however, wheels 60, 61 and 62 simultaneously act upon the upstanding sheet to complete the fold thereof, laying it down upon the right-hand fold already completed. The folded sheet is then still further advanced until its leading end is presented to the opening or gateway in the timed helical member 76, and it is brought to a stop by tray 17. Helical member 76 thereupon acts to raise it from the paper path and add it to the stacked sheets already folded.

The modification shown in Figs. 13 and 14 has a similar action; but instead of employing two suspended folding units the nearer or left-hand unit is fixed with respect to the end frame. Tilted wheels 58 are replaced in this embodiment by wheels 90, spring-pressed by the thinner resilient portion 91 of their support against the gated flanged forming wheels already described. In this embodiment a further forming wheel 92 is added to the series, so that three wheels act 30 formingly upon the sheet in synchronism instead of two. The drive in this case makes use of sprocket wheels 93, attached upon said gated wheels, and upon the drive shaft 20^b driving the same, and of sprocket wheels 94 attached upon the gated sealing wheels 97. These are indicated 40 at their pitch line, and the chain 95 connecting them is indicated by a dotted line. Said chain also acts upon sprocket wheel 96 timing, and through a cam thereon operates the folding knife.

The gated sealing wheels 97 on the left-hand unit are shown in contour in Fig. 13. The corresponding gated sealing wheels 98 on the right-hand unit are indicated in Fig. 14. All of said gated wheels, whether for forming up the sheet 50 or for completing the fold, may be regarded as journaled upon shouldered pins, attached in the case of the left-hand unit upon the end frame, and in the case of the right-hand unit upon the suspended laterally movable sliding frame supporting the mechanism thereof. Cooperating wheels 99 are similarly supported upon shouldered pins. The slight spring pressure required is conveniently furnished by the natural resiliency of said pins. Bearers 110 are indicated to 60 cause said wheels to run smoothly past the recesses.

It will be noted that in the case of this modification the revolvable members are given rotation upon parallel axes. It will be noted also that the operative connection between the left-hand and right-hand folding units is not supplied by a common drive shaft but by individual inwardly projecting pins 100 upon the left-hand members, 70 engaging in holes 101 upon the right-hand members. Said holes are somewhat larger than the pins. Springs 102 act to maintain the pins against the working faces of the holes. It will be noted that I operate the transverse folding 75

rolls likewise through a chain and sprockets, indicated as described before.

The modification operates as has been described, except that the paper path is given an angle upward at 103, the purpose of which is to permit the sealing action of the gated sealing wheels, the angular rise supplying the necessary slack paper. The angle will be smaller or greater according as the wheels are thinner or thicker.

Having thus clearly explained the nature and objects of my invention and the manner of applying the same, I claim as new and desire to secure by Letters Patent,—

1. In a folding machine, in combination: tongue devices and wheel devices, the tongue devices being adapted to support the sheet at the folding line and having a working edge over which a sheet may be bent in a fold by the wheel devices; means for advancing the sheet into the control of the wheel devices; and timed means for causing the wheel devices to engage against the sheet in a folding action.

2. In a folding machine, in combination, a tongue-like forming member, gated wheels adapted to fold a sheet thereover, and means giving said wheels a timed rotation so that the gateways therein will permit the advance of the sheet for delayed folding by said wheels.

3. In a folding machine, in combination, tongue-like forming members, gated wheels axled perpendicularly thereto, and actuating and timing devices to render said wheels effective in folding a sheet over said forming members.

4. In a folding machine, in combination: wheel devices over which a sheet may be folded; folding devices operable to fold a sheet thereover; means for advancing the sheet into the control of said folding devices; and means for giving the folding devices a timed action against the sheet effective to fold it over said wheel devices.

5. In a folding machine, in combination, forming wheels operative at the folding line, gated wheels adapted to bend a sheet thereover, and means giving said gated wheels a timed rotation effective to permit the advance of the sheet into the control thereof prior to the folding action.

6. In a folding machine, in combination, forming wheels, gated wheels adapted to bend a sheet over the working edge thereof, a tongue-like forming member, gated wheels adapted to fold a sheet thereover, and means giving the said several gated wheels a timed rotation effective to permit the advance of the sheet for folding thereby.

7. In a folding machine, in combination: revolvable members adapted to cooperate in flattening a fold entered longitudinally between them, including a wheel axled perpendicularly to the paper path and a wheel axled horizontally to the paper path; and means adapted to advance a folded sheet between said wheels for such fold-flattening.

8. In a folding machine, in combination, a timed reciprocating knife; transverse folding rolls, one thereof supplied with a laterally extending recess or trench adapted to receive the leading edge of the sheet when the same is directed thereinto by said knife, and to carry the same between said rolls without interference and without requiring an intermediate advance of the sheet; means giving said recessed roll a rotation timed to present the recess therein to the sheet-edge; and folding means for folding the sheet entered thereby.

9. In a folding machine, in combination, a timed reciprocating knife; transverse folding rolls, one thereof supplied with a laterally extending trench or recess adapted to receive the leading edge of a sheet when depressed thereinto by said knife, and to permit the same to change its angular position therein, so as to carry the same securely and without interference between said rolls for advancing in usual course by them thereafter; means rotating said rolls, including means timing the rotation of said recessed roll; bearers means for controlling the approach of said rolls at said recess; and folding means effective to fold a sheet entered thereby.

10. In a folding machine, in combination; a timed reciprocating knife; timed transverse folding rolls, each supplied with a laterally extending trench or recess, said recesses adapted to operate at the working edge of the knife to soften the fold produced thereby, and to facilitate the withdrawal thereof, and the cooperating edges thereof to act strippingly upon the knife in advance of closure thereon, without affecting the course of the sheet thereafter; bearers for controlling the approach of said rolls at said recesses; and folding means effective to produce further folds upon the sheet entered thereby.

11. In a folding machine, in combination, separable folding devices, including tongue-like forming members over which a sheet may be folded; threaded means for adjusting the separation of said devices; and a hand-wheel connected to operate said means.

12. In a folding machine, in combination, separable folding devices, including forming devices over which a sheet may be folded and devices adapted to fold a sheet thereover; a plurality of threaded shafts for controlling the separation of said devices; toothed wheels attached thereon; and connecting means adapted to rotate said wheels in unison.

13. In a folding machine, in combination, separable folding devices, including tongue-like forming members, and timed devices adapted to fold a sheet thereover; the operating means therefor; a plurality of threaded shafts for controlling the separation of said separable devices; toothed sprocket wheels attached thereon; and a connecting chain adapted to rotate said wheels in unison.

14. In a folding machine, in combination, laterally separable supporting devices; folding devices thereon, and their operating connections; a plurality of threaded shafts for controlling the separation of said supporting devices; sprocket wheels attached thereon; and a chain for synchronizing the rotation of said sprocket wheels.

15. In a folding machine, in combination, wheels supplied with gated flanges, forming wheels pressed yieldingly thereon over which a sheet may be bent by said flanges, means for timing the rotation of said flanged wheels, and means for folding down the sheet on the folding line established thereby.

16. In a folding machine, in combination, a timed reciprocating knife; spring-pressed rolls rotating in time therewith, each supplied with a cooperating lateral recess; right- and left-hand separable frames; right- and left-hand separable forming devices connected thereto, said devices comprising wheel members over which a sheet may be bent to start a fold and tongue members over which the sheet may be laid down to fold the same; right- and left-hand movable devices on said separable frames, adapted to act inter-

- mittently against the sheet to fold it over said forming devices, said movable devices comprising right- and left-hand gated flanged wheels upon which said wheel members are pressed yieldingly 5 in such manner that the flanges admit the sheet and then bend it thereover, and comprising also right- and left-hand gated wheels having an action intermittently directed against the sheet to fold it over said tongue members, said gated 10 wheels being axled perpendicularly thereto, and being spring-pressed upon cooperating wheels; means giving said movable devices a timed actuation, said means comprising a laterally extending shaft having a key-seat therein, right- and left- 15 hand toothed wheels keyed slidingly thereon, and driving and driven toothed wheels of related dimensions connected thereto; and means for adjusting the separation of said separable frames from a single control, said means comprising a 20 plurality of threaded shafts, sprocket wheels attached thereon, and a chain connecting the sprocket wheels to rotate synchronously.
17. In a folding machine, in combination: a forming member over which a sheet may be bent 25 to make a fold therein; an operable folding member adapted to engage against the sheet to bend or fold it thereover; means for giving the folding member a timed actuation; and timed means for advancing the sheet to be folded into the 30 control of the folding member for folding thereby.
18. In a folding machine, in combination, a forming member and a folding member, the forming member having an edge over which a sheet may be folded and along which the folded 35 sheet may be moved for discharging, and the folding member being adapted to fold the sheet thereover; means for giving one of said members a timed movement adapted to cause the folding of the sheet by the folding member; means for advancing the sheet to be folded into the control of said members; and means effective to discharge the folded sheet from said control.
19. In a folding machine, in combination: a forming member having parallel edges over which 40
- a sheet may be bent in parallel folds; folding devices adapted to engage against the sheet to bend or fold it thereover; means for giving the folding devices a timed actuation; and means for advancing the sheet to be folded into the control of the folding devices for folding thereby. 5
20. In a folding machine, in combination: a forming member having parallel edges over which a sheet may be bent in parallel folds and along which the folded sheet may be moved for discharging; folding devices adapted to bend or fold the sheet thereover; means for giving said folding devices a timed movement; means for entering the sheet to be folded into the control of said devices; and means for discharging the folded 10 sheet from said control. 15
21. In a folding machine, in combination: a forming member having separable edges over which a sheet may be bent in parallel folds; folding devices adapted to bend or fold the sheet 20 thereover; means for giving the said devices a timed actuation; and means for entering the sheet into the control thereof for folding thereby. 25
22. In a folding machine, in combination: co-operating revolvable members, one thereof gated, 30 said members adapted to flatten a longitudinally entered fold in a sheet; means timing the rotation of said gated member; and means adapted to enter a folded sheet for such fold-flattening, said means so timed that the leading edge of the sheet will be received in the aperture of the gated member to avoid its uneven retardation and the consequent distortion of the folding line. 35
23. In a folding machine, in combination: cooperating spring-pressed wheels adapted to flatten a fold entered longitudinally between them, one thereof gated: means adapted to enter a folded sheet for such fold-flattening; and means timing the gated wheel to receive the leading edge of such sheet in the aperture or gateway of the same, to avoid its uneven retardation and the consequent distortion of the folding line. 40
